United States Patent Office.

GEORGE WELLHOUSE, OF AKRON, OHIO.

Letters Patent No. 96,855, dated November 16, 1869.

COOKING-STOVE.

The Schedule referred to in these Letters Patent and making part of the same.

To all whom it may concern:

Be it known that I, GEORGE WELLHOUSE, of Akron, in the county of Summit, and State of Ohio, have invented certain new and useful Improvements in Stoves; and I do hereby declare that the following is a full and complete description of the same, reference being had to the accompanying drawings, making part of this specification, in which—

Figure 1 is a side view of the stove.

Figure 2, a transverse section.

Figure 3, a view of the top.

Figure 4, a longitudinal section.

Figure 5, a detached section.

Like letters of reference refer to like parts in the views presented.

The nature of this invention relates to the construction and arrangement of the flues of a stove, whereby all, or nearly all, of the bottom and back of the oven is exposed to the heat of the fire in its direct draught, thereby increasing the heating-capacity of the stove in relation to the oven, and furthermore, retaining and reinforcing the heat of the walls of the flue by the return draught.

This invention also relates to the fire-grate, which, by giving to it a combined reciprocating, oscillating, and revolving movement, the ashes can be more speedily and thoroughly shaken from the fire-box than can be done in the ordinary way.

In fig. 1, A represents the outside of the stove, B the fire-place, and C, the oven. An inside view of the fire-place, from the top, is shown in fig. 3, the front section of the stove, immediately over the fire, being represented as removed, in order that the inside may be seen.

D, fig. 2, are the side-flues, a side view of which is indicated by the space enclosed by the dotted line a, fig. 1.

These flues, as will be seen in fig. 2, are of a triangular shape, and are formed by the plates E F, the lower edges of which are based against the bottom of the stove at b.

The upper edges approximate and abut against a rib, c, extending lengthwise the stove, forming an arch-like roof to the central return-flue G.

These horizontal flues D G have their corresponding vertical flues D' G' at the rear end of the stove, as seen in fig. 3, the rear walls of flues D' being indicated by the dotted lines C', and which, as will be observed, are of a triangular character, similar to the horizontal side ones above described, and are constructed in the same way, viz, by a pair of plates, indicated by the dotted line C', arranged at an angle to the back of the oven.

The inner edges of said plates meet at the centre of the transverse diameter of the oven at e, against a rib, indicated by the dotted line w, fig. 2, and recede

backward and outward near to the sides of the stove, as indicated by the dotted lines referred to, forming an arch similar to that described of the horizontal flue.

The rear walls of the vertical flues D' also form the front wall of the central flue G', fig. 4, which shows a longitudinal vertical section of the stove.

I, figs. 3 and 4, is a partition-plate, arranged at an angle between the top of the flues and the top of the stove, dividing the area above the flues and oven transversely, and in such relation to the flues that the corner ones, D', are in front on the one side of the plate, and the central flue G' on the other.

Said plate is provided with draught-openings I', extending nearly half way each across the stove, leaving in the middle a narrow piece, whereby the heat is directed under the rear boiler-holes.

I' is a damper, whereby said draught-openings are closed, for a purpose hereinafter shown.

Having thus described the construction and arrangement of the flues, the practical operation of the same is as follows:

The damper I' being closed, as shown in fig. 4, the heat and smoke from the fire-box flow back over the top of the oven, as indicated by the arrows in fig. 5, descend the vertical corner-flues D', thence along the horizontal flues D to the front, as indicated by the arrows in fig. 1; then returning under the oven through the central flue G to the vertical flue G', and from thence to the stove-pipe J. It will be obvious from this that the vertical flues D' and G' are continuations of flues D G.

This arrangement of the flues for direct and return draughts, I do not claim, but that which distinguishes my invention from others is the shape of the flues, and their special construction by means of plates.

Flues as now used are of a somewhat square shape, and cast entire, the capacity of the side-flues being about one-half of the surface of the oven, around which they run, and the centre flue about one-half.

In consequence of the square shape of the flues, the heat, in its way around from the fire-place to the front, is not distributed evenly over the entire surface of the back and bottom of the oven, it being confined to the flues which cover about one-half the surface at the sides, the other half being covered by the return-flue, therefore the oven is unequally heated, the sides immediately covered by the side-flues becoming much hotter than the central part covered by the central flue, which is heated only by the return draught.

This unequal heating of the oven not only interferes with the process of baking, which cannot be uniformly done, but in consequence of the unequal expansion of the plates, occasioned by the unequal heat to which they are exposed, they warp and often crack, thereby seriously injuring the stove.

I am also aware that a single flat plate has been

interposed between the bottom of the oven and the bottom of the stove, thereby dividing the space below the oven into two parts, the upper part for the direct draught and the lower part for the return draught.

By this arrangement the flues are in consequence so low that they soon become filled and choked up with soot and ashes, which is a matter of much trouble to clean out, and becomes, therefore, a serious obstruction to the draught.

In order to avoid these evils, I construct the flues of two plates, E F, above referred to, which, by arranging them at an angle, as shown in fig. 2, viz, bringing the two upper edges together against the rib, forming an arch-like roof to the middle flue G, it will be obvious that larger or deeper flues are obtained than those made by the interposition of a flat plate, and at the same time exposing all, or nearly all, the entire surface of the bottom and end of the oven to the forward draught, thereby distributing the heat, so that the oven will be uniformly heated and in much shorter time, also with less consumption of fuel than can be done by the square flues; also, by this shape of the flues, greater depth is given them than those constructed of a plate. They are less liable to fill up by the deposit of soot and ashes, and, when thus choked up, are cleaned out with less trouble, and more expeditiously, in consequence of their greater depth. Also, the plate referred to, in consequence of its larger size, is liable to warp and crack, and thereby do serious injury to the stove, whereas flues constructed of two plates, and arranged as above described, are much less liable to this defect, hence will be more durable and less expensive to replace when required; also the rib against which the plates abut add to the strength of the bottom of the oven.

On dropping the damper I', as indicated by the dotted line f, fig. 4, shown also in fig. 3, a direct draught is obtained, thereby allowing the heat and smoke to pass immediately to the pipe, instead of being compelled to pass down and around the oven through the flues, as above described.

A further improvement consists in the peculiar construction of the fire-grate K, which consists of a frame, L, hung upon trunnions or shafts M, whereby is obtained to it a revolving and reciprocating longitudinal movement.

In said frame are the bars N, which are pivoted in the sides of the frame, at the points i, fig. 5, the horizontal bars being rigidly attached to the pivots.

To the under side of the bars are attached, in a rigid manner, a pair of semicircular plates, O, fig. 4, the

edges of which are held in a groove, as shown in fig. 2, in which they play, on a revolving motion being given to the frame, and at the same time gives to the bars an oscillating movement when the frame is made to move in a longitudinal direction.

Thus, on pushing the frame in the direction of the arrow, fig. 5, the bars will be made to assume the position indicated in the appended Fig. X, in consequence of the edge of the circular plates being retained in the grooves while the bars move forward.

Now, on reversing the movement of the frame, the bars will thereby change their position to that indicated by the dotted lines a', and so on, as the frame may be continued to be shaken backward and forward, the bars correspondingly change their position.

By this combination of movements, viz, the reciprocating and revolving movement of the entire grate, and the oscillating movement of the bars, the ashes can be easily and thoroughly shaken from the fireplace, and the whole contents thereof can be deposited in the ash-pit by turning the grate to a vertical position, as indicated by the dotted lines n, fig. 4.

At the rear end of the stove are hinged a pair of shelves, P P'. These shelves are for the convenience of placing articles thereon needing to be kept warm, or other articles required to be placed out of the way. These shelves, being hinged to the stove, can be turned up out of the way when not in use, as shown by the lower one P'.

Said shelves are retained in a horizontal position by the check-blocks S, against which the inner edge of the shelf strikes, as shown at P, the upper shelf.

What I claim as my improvement, and desire to secure by Letters Patent, is—

1. The plates E F, as arranged in relation to each other, so as to form an arch-like central flue, G, in combination with the rib c, side-flues D D, and oven O, substantially as and for the purpose set forth.

2. The plate I, as arranged in relation to the flues D and G', in combination with the damper I', for the purpose specified.

3. The oscillating bars N, semicircular plates O, in combination with the shaft M and frame L, in the manner substantially as and for the purpose described.

4. The shelves P P', as arranged, in combination with the stove A, for the purpose specified.

GEO. WELLHOUSE.
